H-PLANE HORN

Lan Jen Chu, Brookline, Mass., assignor, by mesne assignments, to the United States of America as represented by the Secretary of the Navy

Application January 16, 1946, Serial No. 641,606

7 Claims. (Cl. 250—33.65)

1

This invention relates in general to high frequency directive energy transmission and reception, and more particularly concerns the novel structure of an electromagnetic horn of improved radiation characteristics.

An electromagnetic horn comprises, broadly, a flared conductive radiator used for the interchange of wave energy between space and a transmission line and provides a directive or sharply defined radiation pattern. The field pattern obtained by the use of a horn at a particular frequency is a function of the shape and dimensions of the major opening or horn aperture which in turn is determined by the flare angle and horn length. The horn is coupled to a transmission line at the constricted or throat end thereof. The directional properties of the horn are the same for transmission or reception, and the directivity may be effectively increased by the addition of a reflector.

In various applications a horn radiator introduces undesirable features. As an example consider the representative problem of a low angle, or surface search radar system which utilizes a horn for the transfer of energy between a transmission line and a reflector, which in turn provides a radiation pattern with a principal lobe directed toward the horizon and parallel to the earth. The use of a conventional horn radiator results in an overall radiation pattern which includes undesirable side lobes, also parallel to the surface of the earth and at right angles to the principal lobe. Although the energy content of the right angle lobes is considerably less than that of the major lobe, these side lobes will produce on an indicator incorrect and confusing target indications. It is therefore a specific object of my invention to provide an electromagnetic horn radiator having a field pattern including a principal lobe and side lobes oriented such as to eliminate substantially all spurious response.

Another object of my invention is to provide an electromagnetic horn radiator of asymmetrical structure.

A further object of my invention is to provide a horn radiator which in combination with a reflector produces an overall radiation pattern comprising a sharp, directional principal beam and minor side beams elevated with respect to the principal beam.

These and other objects of my invention will now become apparent from the following detailed specification taken in connection with the accompanying drawings in which:

Fig. 1 is a general perspective view of the novel electromagnetic horn of my invention;

Fig. 2 illustrates diagrammatically the combination of the horn of Fig. 1 and a reflecting surface; and

Fig. 3 illustrates the radiation pattern of the horn radiator illustrated in Fig. 2 in a plane passing through the axis III—III of Fig. 2 and normal to the plane of Fig. 2.

10. Referring now to Fig. 1, there is illustrated an electromagnetic horn embodying the principles of my present invention. This horn structure comprises essentially a transmission line extension or input end 11 of substantially rectangular cross section, adapted for coupling to a corresponding rectangular wave guide transmission system (not shown). The longitudinal axis 12 of the rectangular input section 11 comprises also the axis of the horn 10 and indicates the direction of energy transmission therethrough. The horn 10 is a pyramidal conductive structure extending from a rectangular throat section 13 at the junction with input section 11 to a comparatively large rectangular aperture 14. This flared section is 15. constructed of four substantially trapezoidal metallic plates, two of which 15 and 16 are narrow and the other two of which 17 and 18 are comparatively broad.

16. In accordance with the principles of my invention, the plane including the rectangular aperture 14 of the horn is fixed in non-perpendicular relationship with the axis 12 of energy propagation through the horn. The angle between the plane of aperture 14 and the normal to the

30. axis 12 is designated as angle θ on the drawing. The angle between the plane of the rectangular throat 13 and the normal to the axis 12 is also made equal to θ , thereby permitting the broad walls 17 and 18 to be plane trapezoids rather than warped surfaces.

35. The horn illustrated in Fig. 1 may be utilized to interchange energy between a transmission line and space. For example, if the horn is utilized in a transmitter system, energy coupled thereto at rectangular input section 11 will be radiated from the rectangular aperture 14. If the horn is utilized in connection with a receiver, energy intercepted by the aperture 14 will be delivered to the transmission line section coupled at section

40. 11. Energy radiated from the horn of Fig. 1 is directional in nature, and the directivity thereof is primarily a function of the flare angle of the horn between the throat section 13 and the aperture 14. For the pyramidal horn, as illustrated in Fig. 5. 1, the flare angle in the vertical plane is greater

than the flare angle in the horizontal plane and accordingly radiated energy will have a higher degree of vertical directivity. The flare angle actually utilized is dependent upon the particular application of the radiator. In accordance with the well known reciprocal relationship for antennas the energy receiving directivity of the horn is exactly the same as the directivity thereof when used for transmission.

Energy transferred through the horn 10 of Fig. 1 is electromagnetic in nature and includes an electric field component which is parallel to the narrow walls 15 and 16 thereof, and normal to the axis 12. The electric field vector is graphically illustrated at 21. The magnetic field component may be represented by a vector 22 which is normal to both the electric field component 21 and the axis of propagation 12.

It will be noted that the horn 10 has an asymmetrical cross section in a plane taken through the axis 12 and the magnetic field vector 22. The improved performance of the horn 10 resulting from the asymmetrical construction thereof will now be discussed in connection with the diagrammatic representation of an antenna system illustrated in Fig. 2. As illustrated the horn 10 is attached, at rectangular coupling section 11, to a corresponding rectangular wave guide transmission system 31 suitably supported by apparatus not shown in the drawing. The axis 12 is directed at angle θ with respect to the horizontal to a central point of a parabolic reflector 32 secured to an antenna pedestal 33. The particular system illustrated comprises the basic antenna requirement for a surface or low-angle search radar and provides a radiation pattern having a principal lobe 34 directed so that maximum intensity is obtained in a beam parallel to the surface of the earth or sea. A conventional horn, having an aperture cut in a plane normal to the axis of energy transmission, has side lobes due to direct radiation from the horn in a plane common to the principal lobe and the horn axis. The explanation of this lies in the substantially in phase relationship of the aperture illumination which may be thus considered as an effective broadside radiator producing a beam normal to the long edges. Thus side lobes displaced 90° from the horn axis are directed at the horizon. If the principal beam and side lobes of a search radar are all parallel to the earth's surface, target echoes will produce multiple and confusing indications despite the smaller energy content of the side lobes.

For the asymmetrical horn structure of Fig. 1 used in, as indicated in Fig. 2, the phase of the aperture illumination is uniformly variable due to the corresponding uniform variation of distance between points along an edge and the center of throat 13. This phase variation does not eliminate the side lobes but shifts the angle of transmission thereof upward relative to the long edges of the horn aperture so that side lobes displaced 90° from the horn axis are elevated above the horizon.

Fig. 3 illustrates the side lobes 43 and 44 radiated as a result of currents in the vertically positioned edges of the horn 10 shown in Fig. 2. The plane of these side lobes corresponds to the plane of the aperture 14, the aperture being shown in Fig. 3 for clarity. These side lobes 43 and 44 are directed above the horizontal by an angle θ , and are compared with the horizontal side lobes 41 and 42 which would be obtained if the aperture of the horn were cut normal to the axis

thereof. By thus raising the side lobes of the radiation pattern, the aforementioned spurious, multiple response is eliminated in surface search equipment.

A more general analysis of the radiation pattern of the horn 10 indicates that maximum energy is radiated therefrom along the axis 12 as previously described. Energy is also radiated in other directions including the side lobes 43 and 44, and the locus of the vector indicating peak energy radiation in a particular direction forms, essentially, a conical surface generated about the vertical axis III-III, illustrated in Fig. 2 with the center of the aperture 14 as the vertex. When the horn is oriented in the manner illustrated in Fig. 2, peak radiation is horizontal only for the principal lobe 34 and all other radiation is above the horizontal as desired for the specific radar application described above.

It is evident that the asymmetrical horn structure need not be limited to the particular pyramidal design illustrated in Fig. 1. The flare angle and the aperture size will in each instance be determined by the application of the radiator structure. Horns of other cross sectional configuration and other electrical feeds may be utilized to provide similar results if the principles described above are followed.

Thus, since various modifications and extensions of the principles hereinabove set forth will be evident to those skilled in the art, I prefer that the spirit and scope of the present invention be defined not by these specific disclosures but by the appended claims.

What is claimed is:

1. An electromagnetic horn for interchanging energy between a transmission line and space, said horn comprising a flared conductive structure terminating in an aperture at one end thereof and a constricted throat section at the opposite end thereof, said aperture and said throat section substantially lying in parallel planes in non-perpendicular relation with the axis of said horn.

2. An electromagnetic radiation system comprising a wave guide terminating in an aperture, a flared horn having its axial extremities lying in parallel planes, the smaller of said extremities being identical to and continuous with the aperture in said wave guide, and the parallel planes determined by said axial extremities being in non-perpendicular relationship with the longitudinal axis of said wave guide.

3. A directional radiation system for the transmission and reception of a beam of energy comprising, in combination, a reflector, and a wave guide terminating in a flared horn, said flared horn illuminating said reflector and having the extremities thereof disposed in parallel planes in non-perpendicular relationship with the longitudinal axis of said wave guide.

4. A directional radiation system for the transmission and reception of a beam of energy comprising, in combination, a reflector, a wave guide, and a flared horn integral with said wave guide illuminating said reflector, the junction of said horn with said wave guide and the termination of said horn lying in parallel planes in non-perpendicular relationship with the longitudinal axis of said wave guide.

5. A directional antenna system for the transmission and reception of a beam of energy comprising, in combination, a reflector, a wave guide having its longitudinal axis angularly displaced from the axis of said beam of energy, a flared

horn having its smaller end integral with the end of said wave guide, both smaller and larger ends of said flared horn lying in parallel planes in non-perpendicular relationship with the longitudinal axis of said wave guide.

6. A directional antenna system comprising, a parabolic reflector for forming a substantially pencil-shaped beam of energy, a rectangular wave guide, and an electromagnetic horn of conductive material formed by flaring out the walls 10 of said wave guide, the junction of said wave guide and one extremity of said horn comprising a rectangular aperture, the opposite extremity of said horn comprising a larger rectangular aperture lying in a plane parallel to the plane of said first-mentioned rectangular aperture, said planes being in non-perpendicular relationship with the longitudinal axis of said wave guide and normal to the axis of said beam of energy.

7. In a radar system having an antenna for providing a major beam of energy having an axis lying in a first plane, apparatus for rendering minor beams of energy ineffective in said system comprising, a transmission line and an electromagnetic horn for distributing energy upon the 20 surface of said reflector, said electromagnetic horn terminating in apertures lying in second

and third parallel planes, said transmission line being joined to said electromagnetic horn in said second plane, said second and third planes being nonperpendicularly related to the axis of propagation of energy in said electromagnetic horn, said axis of propagation of energy being a continuation of the axis of said transmission line and being at an acute angle to said first plane.
